UNITED STATES PATENT OFFICE.

EDWIN J. PRINDLE, OF WASHINGTON, DISTRICT OF COLUMBIA, ASSIGNOR
TO THE PREMIER LAST COMPANY, OF GREAT RIVER, LONG ISLAND,
NEW YORK, A CORPORATION OF NEW YORK.

LAST.

No. 853,827.

Specification of Letters Patent.

Patented May 14, 1907.

Application filed January 26, 1900. Serial No. 2,854.

To all whom it may concern:

Be it known that I, EDWIN J. PRINDLE, of Washington, in the District of Columbia, have invented certain new and useful Improvements in Lasts; and I do hereby declare that the following is a full, clear, and exact description thereof, reference being had to the accompanying drawings, in which—

Figure 1 is a side elevation of a form of my improved last in which the only connection between the fore and heel part, is my shiftable pintle. Fig. 2 is a vertical, longitudinal, sectional view taken on the line $x-x$ of Fig. 3. Fig. 3 is a top plan view of the form of last shown in Fig. 1. Fig. 4 is a perspective view of the form of connection used between the fore and heel parts in the last which is the subject of illustration in Figs. 1, 2 and 3.

The object of my invention, is to produce a divided last having a connection or part between the fore and heel parts, which can be shifted to a position preferably near the bottom of the last to permit shortening the last, to permit of the easy insertion and removal of the last from the shoe, and which connection or part can be shifted to lock the last in its extended position, thus preventing its collapse under the tension of the upper, and connecting the fore and heel parts at such a distance from the bottom of the last as to give the greatest strength that is possible in a divided last. And to this end my invention consists in the construction herein-after described and claimed.

In the form of last shown, the last has a fore part A, which is divided from the heel part B by a vertical cut, and the upper and forward portion of the heel part B is removed by a downward cut which is inclined forward to meet the surface of the fore part B at a point d near the bottom of the last, thus forming a V-shaped space between the fore part A and the heel part B, to enable the latter to be swung forward. Two plates C' are secured in vertical, longitudinal slots in the fore part A by pins C^3 , passing through the fore part and through holes C^4 in the plates C' . Two plates C^2 are likewise secured in slots in the heel part B by pins C^3 which are driven through the heel part and through holes C^4 in the plates C^2 . The plates of the heel part lie between the plates of the

fore part, though the heel part plates might lie outside of the fore part plates; and each of the four plates is provided with a slot C^7 , extending from a point near the upper surface of the last to a point near the bottom of the last. The bottom curves of the slots are concentric with the point of intersection d between the rear surface of the fore part and the inclined surface B of the heel part. A pintle C occupies the slots of the four plates and thus connects the fore and heel parts of the last. Slots A' are cut in the fore part A to permit the plates C^2 of the heel part to enter the fore part when the heel part is swung forward, and slots B^2 are cut in the heel part to receive the plates C' of the fore part at the same time. One of the plates C' on the fore part A might be dispensed with and one of the plates C^2 of the heel part B also dispensed with, if desired, and flanges be formed on the pintle to keep it in place, thus simplifying the construction. Such construction is shown and claimed in Letters-Patent No. 648,525, granted to me May 1, 1900.

As the last is in the normal position, or right side up, when the pintle is used at the bottom of the slots C^7 , no means are necessary to retain it in that position, its own weight being sufficient; but when the pintle is used at the top of the slots, it is convenient but not necessary to have some retaining means. The pintle shown, is circular in cross-section except at the ends where it occupies the slots C^7 in the plates. On these ends it is flattened, and the width of the slots C^7 , except at the top, corresponds to the width of these flattened ends. At the top, however, each slot C^7 is enlarged or offset. The slots C^7 may, if desired, be offset at the bottom to provide for locking the pintle in the lower position. The pintle is provided with a handle C^6 , which may, if desired, be made long enough to be within reach when the pintle is at the bottom of the slots, said handle consisting of a strip of sheet metal, set into the body of the pintle; and when the pintle is raised (by the use of an ordinary last hook,) the pintle is turned by the handle; and, the flattened ends of the pintle occupying the enlarged ends of the slots with some friction, the pintle is locked in place. The same movement will, if there be enlargements at

the bottom of the slots, lock the pintle at such points.

In the form of last described, the plates C' and C² connecting the fore and heel parts project over a portion of the part of the last which is opposite to that part to which they are attached. For instance, the plates C' attached to the fore part A project over the material of the heel part which is near the bottom, and the plates C² which are attached to the heel part B project over the material of the fore part A, which is near the bottom. This prevents either part of the last from moving up or down on the other. For, the plates C' on the fore part A prevent the heel part B from rising, and the plates C² on the heel part, by projecting over the fore part, prevent the heel part B from falling. While this construction is not necessary it is desirable as it aids in keeping the fore and heel parts in proper relation when the shiftable pintle is not locked in the enlargements at the ends of the slots. This construction may, however, be dispensed with and the pintle alone be depended upon to keep the plates and through them the last parts in suitable relation.

The operation of this form of my last is as follows:—To insert the last in the shoe, the pintle is pushed down, with an ordinary last hook, to the bottom of the slots. The heel part is now swung forward, and, the pintle being near the bottom of the last, a marked shortening is obtained. The fore part of the last is pushed well into the toe of the shoe, and the heel part is pushed down against the sole. This last hook is then caught under the pintle and the latter raised to the top of the slots. The last in this condition is locked against the collapsing tension of the upper and also against breaking strain such as that of the sole leveling machine. When the last is to be removed, the pintle is pushed to the bottom of the slots. The heel part is now easily swung forward, since the position of the pintle near the bottom of the last causes it to recede from the counter at the beginning of its upward movement, and the last can be removed.

5c While I have shown the recess between the last parts as located in the upper portion of the last, and the heel part as swinging over the pintle, in shortening the last, I can locate the recess in the lower portion of the last and cause the heel part to swing under the pintle in shortening the last, and in such construction the locking position of the pintle would be the one nearer the sole, and the unlocked position of the pintle would be the one farther from the sole.

1. In combination with a divided last having a portion removed between the fore and heel-parts forming a recess lying transversely of the last when extended, overlapping plates, each of which is secured to one of the last

parts and projects into said recess, and means for locking said plates together, such means consisting of a bodily and axially movable locking piece, said plates having locking surfaces which are engaged by said locking piece when said locking piece is turned into one position, and which are not engaged thereby when said locking piece is occupying another position.

2. A jointed last having rigid pieces on the fore and heel-parts and having a single movable part forming a connection between the rigid pieces which is bodily movable with relation to both of said pieces, substantially as described.

3. A jointed last having rigid pieces on the fore and heel parts and having its fore and heel parts bearing against each other, and having a single movable part forming a connection between the rigid pieces, said connection being bodily movable with relation to both of said pieces, substantially as described.

4. A jointed last having rigid pieces on the fore and heel parts and having its fore and heel parts bearing against each other at the bottom, and having a single movable part forming a connection between the rigid pieces, said connection being bodily movable with relation to both of said pieces, substantially as described.

5. A jointed last having rigid pieces on the fore and heel parts and having a single movable part forming a connection between the rigid pieces, said connection being movable to positions toward and from the bottom of the last one of which permits the shortening of the last, and the other of which causes it to be locked, substantially as described.

6. A divided last having rigid pieces on the fore and heel parts and having a single movable part forming a connection between the rigid pieces, said connection being movable to a position toward the bottom of the last, in which position the connection permits the shortening of the last, and said connection being movable to a position away from the bottom of the last, in which position the connection locks the last, substantially as described.

7. A divided last having rigid pieces on the fore and heel parts and having its fore and heel parts bearing against each other and having a single movable part forming a connection between the rigid pieces, said connection being movable to positions toward and from the bottom of the last that permit a swinging movement of the heel-part, and cause the last to be locked, substantially as described.

8. A divided last having rigid pieces on the fore and heel parts and having its fore and heel parts bearing against each other at the bottom and having a single movable part forming a connection between the rigid

pieces, said connection being movable to a position toward the bottom of the last in which position the connection permits the shortening of the last, and said connection being movable to a position away from the bottom of the last, in which position the connection locks the last, substantially as described.

9. A divided last having a pintle, rigid pieces on the fore and heel parts, which, with the pintle, connect the fore and heel parts, and which pintle is bodily movable with relation to both of said pieces, substantially as described.

10. A divided last having its fore and heel parts bearing against each other at the bottom, and having rigid pieces on the fore and heel parts, a pintle which, with said pieces, connects the fore and heel parts, and which pintle is bodily movable with relation to both of said parts.

11. A divided last having its fore and heel parts bearing against each other at the bottom, having rigid pieces on the fore and heel parts, and a pintle connecting such pieces, said pintle being bodily movable with relation to both of said parts.

12. A divided last having a plate attached to the fore part, a plate attached to the heel part, each plate having a slot therein, and a pintle situated in said slots and connecting said plates, substantially as described.

13. A divided last having a slotted plate attached to the fore part, a slotted plate attached to the heel part, the fore and heel parts abutting, and a pintle situated in said slots and connecting said plates, substantially as described.

14. A divided last having a slotted plate attached to the fore part, a slotted plate attached to the heel part, the fore and heel parts abutting at the bottom of the last, and a pintle situated in said slots and connecting said plates, substantially as described.

15. A divided last having a single connec-

tion between the fore and heel parts, said connection being movable to positions toward and from the bottom of the last, that respectively permit the shortening of the last and cause it to be locked, and means to hold said connection in the last-locking position, substantially as described.

16. A divided last having a slotted plate attached to the fore part, a slotted plate attached to the heel part, the fore and heel parts abutting, a pintle situated in said slots and connecting said plates, and means to hold said pintle in the last-locking position, substantially as described.

17. A divided last having a plate attached to the fore part, a plate attached to the heel part, each plate having a slot therein which slot has substantially parallel sides, a locking piece occupying said slots, said slots having enlargements at the points where it is desired to hold the locking piece from movement, substantially as described.

18. A divided last having a plate attached to the fore part, a plate attached to the heel part, each plate having a slot therein which slot has substantially parallel sides, a locking piece occupying said slots said locking piece having an end whose thickness is substantially that of the parallel sided slots and whose width is greater than its thickness, said slots having enlargements at points where it is desired to hold the locking piece from movement, and means whereby the locking piece can be turned so that the greater dimension of its end can lie across the direction of the slots in the enlargements thereof, substantially as described.

In testimony that I claim the foregoing I have hereunto set my hand this 26th day of January, A. D., 1900.
